(57) **CLAIM**

The ornamental design for a combination air filter and ventilating fan, as shown and described.

DESCRIPTION

FIG. 1 is a front top perspective view of a combination air filter and ventilating fan.

FIG. 2 is a front view thereof.

FIG. 3 is a right view thereof.

FIG. 4 is a back view thereof, showing a drawer in a closed position.

FIG. 5 is a left view thereof.

FIG. 6 is a top view thereof.

FIG. 7 is a bottom view thereof; and,

FIG. 8 is a back top perspective view thereof, showing the drawer in an open position.

The broken lines shown in FIGS. 1-8 are included to show portions of the combination air filter and ventilating fan that form no part of the claimed design.

1 Claim, 8 Drawing Sheets
